Fig. 4

Fig. 5

Fig. 6

Fig. 7

FIG. 1 is a perspective view of a sewing machine embodying my new design, showing the front and one end and part of the top thereof,

FIG. 2 is a perspective view of the same, showing the front and the opposite end, with part of the top,

FIG. 3 is a front elevation thereof,

FIG. 4 is an elevation of the end seen on the right in FIGS 2 and 3,

FIG. 5 is a rear elevation thereof,

FIG. 6 is an elevation of the end seen on the left in FIGS. 1 and 3, and

FIG. 7 is a top plan view of the same.

The essential features of my design reside in the portions shown in full lines.

I claim:

The ornamental design for a sewing machine, as shown and described.
